45° ELBOW CONDUIT FITTING

Leonard J. Grunwald, Denver, Colo., assignor to Screw Machine Products Co., Denver, Colo., a corporation of Colorado

Filed Sept. 9, 1968, Ser. No. 13,455

Term of patent 14 years

Int. Cl. D23—02

U.S. Cl. D23—40

FIG. 2

FIG. 1

FIG. 3

FIG. 4

FIG. 1 is a perspective view of a 45° elbow conduit fitting showing my new design;

FIG. 2 is an elevational view taken from one side thereof, the opposite side being a mirror image of the side shown;

FIG. 3 is a front elevational view thereof;

FIG. 4 is a cross sectional view taken on line 4—4 of FIG. 2.

The broken line representation of pipe fittings in FIG. 1 is for purposes of illustration only.

I claim:

The ornamental design for a 45° elbow conduit fitting, as shown and described.
